UNITED STATES PATENT OFFICE.

JOHN CIRUCKI, OF SHENANDOAH, PENNSYLVANIA.

COMBINED FIREARM AND SWORD.

1,052,316.

Specification of Letters Patent.

Patented Feb. 4, 1913.

Application filed June 8, 1912. Serial No. 702,451.

To all whom it may concern:

Be it known that I, JOHN CIRUCKI, a citizen of the United States, and a resident of Shenandoah, in the county of Schuylkill and State of Pennsylvania, have invented a new and Improved Combined Firearm and Sword, of which the following is a full, clear, and exact description.

This invention relates to improvements in weapons, and particularly to combined weapons wherein a plurality of independent offensive and defensive weapons are combined in one instrument.

The object in view is to provide a combined instrument having co-acting members which may be used simultaneously or independently for offensive and defensive warfare.

Another object of the invention is to provide a firearm structure on the grip of a sword and to so arrange the same that the sword and the firearm may be used independently, and that the end of the sword and one end of the guard may be used as sights for the firearm.

Still another object of the invention is to provide a firearm arranged to automatically fire upon the depression or operation of a trigger member.

A practical embodiment of the invention is represented in the accompanying drawings forming a part of this specification, in which similar characters of reference indicate corresponding parts throughout all the views.

Figure 1 is a side view of an embodiment of the invention; Fig. 2 is a top plan view of the structure shown in Fig. 1; Fig. 3 is a view of the structure shown in Fig. 1 looking from the opposite side, part of the sword being broken away; Fig. 4 is an enlarged longitudinal vertical section through Fig. 2 substantially on the line 4—4, certain parts being shown in elevation; Fig. 5 is a similar section to that shown in Fig. 4, with the mechanism shown in position for future firing; Fig. 6 is a section through Fig. 5 substantially on line 6—6; Fig. 7 is a similar view to that shown in Fig. 5 except that certain parts are broken away and the mechanism is shown in the cocked position; Fig. 8 is a section through Fig. 4 substantially on

the line 8—8; Fig. 9 is a section through Fig. 4 on the line 9—9; Fig. 10 is a section through Fig. 5 substantially on the line 10—10; Fig. 11 is a fragmentary bottom plan view of the trigger and associated mechanism; and Fig. 12 is a fragmentary side view showing the ejecting cam.

Referring to the accompanying drawings by numerals, 1 indicates the blade of a sword or saber having a point 2 and a guard 3. The guard 3 is connected at 4 to a grip 5 in any desirable manner, and is provided with a sighting point 6 which, together with the point 2, provide means for sighting the firearm 7 connected with the sword. The guard 3 is provided with a suitable aperture through which the barrel 8 of the firearm 7 projects, and which holds the firearm in place, the remaining part of the firearm being properly held in place by a suitable retaining screw 9 and by being formed partially from the grip 5, as hereinafter fully described.

The barrel 8 is provided with the usual chamber 10 in which a cartridge may be forced whenever desired. Adjacent the chamber is arranged a cut-out portion or cartridge discharge aperture 11. Arranged below or opposite the aperture 11 is a magazine 12 having a follower 14 pressed by a spring 15. The spring 15 engages the bottom 16 in the usual manner and continues to press the follower 14 whereby the cartridges above the follower are continually urged toward the aperture 11. The cartridges, as the same are fed from the magazine, strike against the lower surface of an ejecting stop or cam 17 and against the housing 18. This places the cartridges in the path of movement of a bolt 19 which is designed to force the cartridges into the chamber 10, as clearly shown in Fig. 4.

After a cartridge has been forced into the chamber 10 the cocking lever 20 may be released and the firing pin 21 may be permitted to strike, whereby an explosion will occur and the bullet will be forced in the usual manner from the barrel 8, and at the same time the recoil will cause the cartridge to press or force the bolt 19 back to substantially the position shown in Fig. 7. This will cause the lower edge of the cartridge

shell to strike against the end of the ejecting stop 17, while the upper part of the cartridge is held by the extractor 22. By thus being pulled at one edge and pushed at the other the shell will be thrown out of the housing 18 and a new filled cartridge will immediately take its place.

The firing pin 21 is actuated by a spring 23 pressing against a shoulder 24 rigidly secured to the firing pin. The cocking lever 20 is provided with a slot 25 and is thus pivotally and loosely connected with the pin 21 so that though the trigger is moved pivotally the pin 21 may be freely reciprocated. The cocking lever 20 is loosely pivoted on a shaft 26 mounted in an enlargement 27 of the bolt 19. The enlargement 27 is formed with a spring retaining projection 28 for holding the spring 29 in place, and also has depending shoulder portions 30 and 31. The cocking lever 20 is provided with a lug 32 having a cam face 33 designed to strike against the lower surface 34 of the depending shoulder portion 31, and by reason of the shape of these parts the cocking lever 20 is moved to one side or longitudinally of the shaft 26 until the lug 32 has moved to a position above the shoulder portion 31. A spring 35 surrounds the shaft 26 and normally presses the cocking lever 20 toward the shoulder portion 31 so as to cause the stop 32 to engage the same whenever not positively held therefrom. A thumb operated reciprocating pin 36 is provided for forcing the lug 32 of cocking lever 20 out of engagement with the shoulder portion 31 so as to permit the spring 23 to act. When it is desired to lock the cocking lever 20 against operation a substantially U-shaped member 37 is moved to a position below the end of the cocking lever 20, as clearly shown in Fig. 4, whereby the cocking lever is not permitted to swing. The U-shaped member 37 is provided with a hand-operated pin 38 slidingly mounted in a crank 39 whereby the U-shaped member 37 may be shifted from the position shown in Fig. 4 to the position shown in Fig. 5. A suitable aperture 40 is provided for the pin 38 for locking the U-shaped member 37 against movement when in the position shown in Fig. 4, whereby the cocking lever cannot be tripped and consequently the firing pin cannot be operated.

The housing 18 merges into a casing 18' at the rear for protecting and holding spring 29 properly in place. The spring 29 is designed to rest against the end 41 so as to normally press against the bolt 19. The casing 18' is substantially U-shaped in cross section and is held rigidly in position at the end 41 by a suitable bolt or screw 9. The casing 18' and a substantially L-shaped member 42 forming part of the guard 3 provide means for inclosing the operating or moving parts of the firearm, and in addition

means for journaling the U-shaped member 37, as well as the cam 43, for engaging the cocking lever 20 when cocking the same.

In operation, when it is desired to fire the firearm or prepare the same for such an emergency, the end 44 of the rod 45 is pulled or moved longitudinally, whereupon the hook portion 46 thereof will engage the shoulder portion 30 and move the bolt back to substantially the position shown in Fig. 7, whereupon the cocking lever and firing pin are cocked and the lug 32 is caused to snap over the shoulder portion 31. Upon releasing the rod 45 the spring 29 will force the bolt 19 to the position shown in Fig. 4, and the bolt will carry with it the cartridge fed from the magazine 12. If it is not desired to use the firearm immediately, the pin 38 is moved, as well as the U-shaped member 37, until the U-shaped member 37 occupies substantially the position shown in Fig. 4, which will lock the cocking lever against future movement, whereby the firearm cannot be fired even if the pin 36 is depressed. When it is desired to discharge the firearm the U-shaped member is moved from the position shown in Fig. 4 to substantially the position shown in Figs. 5 and 7, and then the pin 36 is depressed until the stop 32 is forced from the shoulder portion 31. This will permit the cocking lever to move freely on its shaft 26, and will also permit the firing pin to strike a cartridge. Upon explosion of the powder in the cartridge the bullet is, of course, propelled out of the barrel of the firearm, and the cartridge shell is forced to the rear, together with the bolt 19 and associated parts, until the shell strikes against the ejecting stop 17, whereupon the shell is thrown out. When the bolt is forced back to the position shown in Fig. 7 the cocking lever 20 is cocked and the stop 32 carried thereby is forced over the shoulder portion 31. If the pin 36 is not depressed the bolt 19 will make a return movement to the position shown in Fig. 4, but the firing pin will be held against striking. However, if pin 36 is held depressed so that the stop 32 cannot move on to the shoulder portion 31, the cocking lever will be permitted a free pivotal movement so that the firing pin will be allowed to strike as soon as the cartridge has been forced into the chamber 10. This back and forth action will be continued automatically as long as the pin 36 is held depressed and there are cartridges remaining in the magazine. The firing may be stopped at any time by merely releasing the pin 36. It will be noted that the aperture 11 is set back farther toward the rear from the barrel 8 than the upper end of the magazine 12. This is to allow the cartridges to be properly fed to the housing 18 without permitting the same to pass on through the aperture 11. A covering 47, preferably of

leather, is provided for the grip and may be secured thereto by any desired means.

Having thus described my invention, what I claim as new and desire to secure by 5 Letters Patent is:—

1. In a device of the character described, a firearm structure including a barrel, a housing, a magazine for feeding cartridges to said housing, a bolt for forcing said 10 cartridges from said housing into said barrel, a firing pin arranged in said reciprocating bolt, a spring for forcing said firing pin in one direction, a pivotally mounted cocking lever formed with a slot in one end, 15 means connected with said firing pin and extending through said slot whereby when said cocking lever is moved in one direction said firing pin will be moved against the action of said spring, a cam for moving 20 said cocking lever so as to bring said firing pin to a cocked position, means for holding said cocking lever in a cocked position, a swinging member adapted to be swung into the path of movement of said cocking 25 lever for acting as a safety lock for the cocking lever, and a reciprocating pin adapted to press against said cocking lever for disengaging the same from its holding means after said swinging member has been 30 moved out of the path of movement of the cocking lever.

2. In a device of the character described, a firearm structure including a barrel, a housing, means for feeding cartridges into 35 said housing, a reciprocating bolt, a firing pin arranged in said reciprocating bolt, a spring for forcing said firing pin in one direction, a pivotally mounted cocking lever formed with a slot in one end, means 40 projecting from said firing pin into said slot whereby when said cocking lever has been moved said firing pin will be moved, a cam for moving said cocking lever to such position as to cause said firing pin to be 45 cocked, a shoulder portion extending from said reciprocating bolt, a stop extending from said cocking lever adapted to engage said shoulder portion for holding said cocking lever in a cocked position, a safety lock 50 adapted to engage and hold said cocking lever against movement when said safety means are moved to a predetermined position, and a reciprocating member adapted to move said stop off of said shoulder portion for releasing the cocking lever whereby 55 said firing pin is permitted to strike.

3. In a device of the character described, a blade, a guard therefor, a hollow grip portion formed with a hand gripping end 60 and a tubular end, a barrel connected with said tubular end including a cartridge receiving chamber, a magazine fitting into said guard and engaging part of said grip portion for feeding cartridges into said 65 tubular end, a reciprocating bolt for engag-

ing said cartridges and forcing the same into said chamber, a spring engaging one end of said bolt positioned in said grip portion for operating said bolt, a reciprocating firing pin arranged in said bolt, a cocking lever 70 operating said firing pin, means for locking said cocking lever against operation, and means for releasing said cocking lever.

4. In a device of the character described, a firearm structure including a barrel, a 75 housing, a magazine for feeding cartridges into said housing, a reciprocating bolt formed into a hollowed portion or chamber, a firing pin arranged in said reciprocating bolt, one end projecting into said chamber, 80 a spring acting on said firing pin for continually tending to cause the same to move in one direction, a cocking lever pivotally mounted on said bolt in said chamber, said cocking lever being formed with a slot in the 85 end, means extending from said firing pin into said slot whereby said cocking lever is adapted to manipulate said firing pin, means for cocking said cocking lever, a stop projecting from said cocking lever, a shoulder 90 portion projecting from said bolt for engaging said stop, and a movable manually operated member for forcing said stop off of said shoulder whereby said cocking lever is released and said firing pin is permitted to 95 strike.

5. In a device of the character described, a barrel, a housing associated with said barrel formed in the shape of a sword guard, a sword connected to said housing, a 100 reciprocating bolt arranged in said housing, a magazine for feeding cartridges into said housing, said bolt being adapted to force said cartridges into said barrel, a reciprocating pin arranged in said bolt for firing 105 said cartridges, a pivotally mounted cocking lever for retracting said reciprocating pin, a shoulder portion arranged on said housing, a stop arranged on said cocking lever adapted to engage the shoulder portion 110 whereby said lever is held against movement after the same has been cocked, resilient means for forcing said stop into engagement with said shoulder portion, and manually operated means for forcing said 115 stop out of engagement with said shoulder portion for releasing the cocking lever and the reciprocating pin.

6. In a device of the character described, a firearm structure including a barrel, a 120 housing, a magazine for feeding cartridges into said housing, a reciprocating bolt, a firing pin arranged in said reciprocating bolt, a spring for forcing said firing pin in one direction, a cocking lever pivotally mounted 125 centrally formed with a slot, a journal member connected with said firing pin for projecting into said slot whereby when said cocking lever has been moved said firing pin will be moved, a cam for moving said 130

cocking lever whereby said firing pin will be cocked, a catch for holding said cocking lever in its cocked position, a pivotally mounted safety lock for locking said cocking lever against movement, and means for unfastening said catch after said safety lock has been thrown off.

In testimony whereof I have signed my name to this specification in the presence of two subscribing witnesses.

JOHN CIHUCKI.
